UNITED STATES PATENT OFFICE.

ROBERT M. CUSHMAN, OF FRANKLIN PARK, NEW JERSEY.

IRON CAR-FRAME.

SPECIFICATION forming part of Letters Patent No. 307,846, dated November 11, 1884.

Application filed June 9, 1884. (No model.)

To all whom it may concern:

Be it known that I, ROBERT M. CUSHMAN, of Franklin Park, in the county of Somerset and State of New Jersey, have invented an 5 Improvement in Iron Car-Frames, of which the following is a specification.

My invention relates to that class of iron car frames or platforms in which tubes are employed running longitudinally in pairs; 10 and the said invention consists in a metal transom-beam constructed to receive the said tubes and the king-bolt; also, in the end beams of the platform, that are made so as to protect the tubes in case of concussion from collision 15 of two trains, and also in the connecting devices between the draft-frame and the tubular platform.

In the drawings, Figure 1 is a plan view, partially in section, of the platform at one end 20 of the car. Fig. 2 is a longitudinal section at *x*. Fig. 3 is a cross-section of the transom-beam at *y*, and Fig. 4 is a similar view of a slight modification in the plates of the transom-beam.

The tubes *a* are used in pairs, one above 25 the other. They are united together by clamps or bands *B* with intermediate blocks, in a manner similar to that shown in Letters Patent No. 243,430, and the stake-pockets *w* and vertical studding *o* are to be of a similar character 30 to that shown in Letters Patent No. 236,786; or these parts may be of any other suitable construction—such, for instance, as shown in Letters Patent No. 243,762.

The ends of the platform are composed of 35 three metal plates, *a*, *a*, *a*, with two intermediate planks of wood, *b*, *b*, and the ends of the tubes pass through the inner plate, *a*, and plank *b*, and abut against the center plate, *a*. The inner plate, *a*, rests against the end clamp- 40 bands, *B*, and a bolt, *c*, passes through the plates *a*, *a* and plank *b* into each tube, such bolt being secured in any convenient manner in the tube, either by having the body of the bolt large enough to fill the tube, as seen 45 in Fig. 1, and secured by a cross-bolt or rivet, or else there may be a nut fastened in each tube, into which the bolts may be screwed. By this construction the platform end is firmly 50 secured to the tubes, and in case of collision the wood planks and plates may be broken,

and the risk of injury to the tubes will be lessened. The tie-rods *m*, also shown in said Patent No. 243,762, pass through the said platform end, and serve to bind the same firmly against the ends of the tubes *a*. 55

The transom-beam is made for receiving the king-bolt *e* and circular bearing-plate *f*, that connect the car-platform to the truck-frame *g*. There is nothing unusual in these parts *e*, *f*, *g*, and they may be of any known character. The transom-beam itself is made of the top plate, *h*, and the lower or brace plate, *h*. The latter is either passed above the lower tubes of the two middle ranges of tubes, as seen in Fig. 3, or below the same, as seen in Fig. 4. In both instances the plate *h* is bent 60 diagonally at each side of the bearing-plate *f*, so as to extend up to the top plate, *h*, and the end portions of *h* and *h* lie flat against each other, and are welded or riveted. 65

There is a clip-piece, 10, upon the end of *h*, outside the outer tube, *a*, and another clip-piece, 11, at the inner side of the said tube. These are bolted or riveted to *h*, and not only clip and hold the tube, but the inner 75 piece, 11, forms a saddle for the tie-rod *m* to pass over. Similar clip-pieces, 10 and 11, are applied upon the surface of *h* at the sides of the inner longitudinal tubes, *a*. 7c

At the center part, between the plates *h*, *h*, there is a king-bolt bearing, *l*, in the form of an open box or frame, with external flanges that are bolted or riveted to *h*, *h*, and the king-bolt *e* passes through the bottom part of this frame into the bearing-plate on the truck-frame. 80

The strut-pieces *n* are made with flanges, and they are adapted to set between the plates *h*, *h* of the transom-beam, and between the upper and lower longitudinal tubes, *a*, of the middle ranges of tubes. When the plate *h* passes over the lower tubes *a*, as in Fig. 3, there will be a clip-piece, 14, around the tube, as shown; but when the plate *h* is below the lower tubes *a*, as in Fig. 4, then the lower ends of the strut-pieces *n* will be arched 90 to pass over said tubes. 95

The brace-bars *o*, extending from the lower tubes of the outer pairs of tubes to the plate *h*, may either pass horizontally, as in Fig. 4, 100

or at an inclination, as in Fig. 3, there being blocking-pieces between the tubes at the outer pairs of tubes a .

Upon the truck-frame there are the ordinary bolster or bearing blocks, 16, and upon the transom-beam there are the shoes 17. These are bolted to the plates h^2 and h^3 , and the struts 18 serve to keep the plates h^2 h^3 at the proper distance apart where the bolts pass through them.

Between the transom-beam and the end beam I introduce two parallel tubes, r' , with bolts passing through them, and through the transom-beam and through the end beam, and 15 nuts at r^3 hold the parts firmly together. The draft-frame s' is provided with a buffer-head, that is adapted to receive the link or other coupling.

At the inner end of the draft-frame is a bolt, 20 s^2 , that passes through the cross-heads s^3 s^4 , the ends of which are made with semicircular recesses to slide upon the parallel tubes r' , and there is a cross pin or head to this bolt s^2 and a helical spring, s^5 , around such bolt s^2 , 25 and around the parallel tubes r' are the abutment-tubes r^4 r^5 , with enlarged ends or collars, the tubes r^4 being between s^3 and a^4 , and the abutment-tubes r^5 being between the cross-head s^4 and the transom-beam. By this construction the spring s^5 is compressed between 30 s^4 and s^3 . When the train is in motion, the abutment-tubes r^4 resist and prevent motion

of the cross-head s^3 ; but when the buffer is pressed inwardly it carries with it the cross-head s^3 and compresses the spring s^5 , the cross-head s^4 remaining immovable and supported by the abutment-tubes r^5 .

I claim as my invention—

1. The combination, with the pairs of longitudinal tubes a , of the end beams composed 40 of the metal plates a^2 a^3 a^4 and intermediate wooden plank, b^2 b^3 , the tubes passing at their ends into the plank b^3 , and the bolts securing the parts to the tubes, substantially as set forth.

2. In the transom-beam, the plates h^2 h^3 , in 45 combination with the tubes, clip-pieces, and struts, substantially as set forth.

3. The abutment-tubes r^4 r^5 and parallel tubes r' , secured between the end beam and the transom-beam, in combination with the 50 cross-heads s^3 s^4 , spring s^5 , and draft-frame and buffer, substantially as set forth.

4. The combination, with the longitudinal tubes a a , end beam, and transom-beam, of the clips 10 and 11, fastened upon the transom-beam, and the tie-rods m , passing over the saddle formed upon the clip 11, substantially as set forth.

Signed by me this 4th day of June, A. D. 1884.

R. M. CUSHMAN.
